UNITED STATES PATENT OFFICE.

CHARLES C. LANE, OF LOS ANGELES, CALIFORNIA.

ORE-CRUSHING MACHINE.

SPECIFICATION forming part of Letters Patent No. 709,822, dated September 23, 1902.

Application filed November 18, 1899. Serial No. 737,518. (No model.)

To all whom it may concern:

Be it known that I, CHARLES C. LANE, a citizen of the United States, residing at Los Angeles, in the county of Los Angeles, State 5 of California, have invented new and useful Improvements in Ore-Crushing Machines, of which the following is a specification.

My invention relates to improvements in that class of ore-crushing machines in which 10 crushing-rolls are caused to travel upon dies formed of bars situate in the bottom of an annular trough which forms the tread for the rolls; and the object thereof is to provide a machine of simple construction that will 15 crush the ore to a predetermined degree of fineness, depending upon the distance apart of the bars forming the tread of the rolls. I accomplish this object by the mechanism described herein and illustrated in the accompanying drawings, in which—

Figure 1 is a plan view of my ore-crusher with the crushing-rolls and parts of the frame and shaft removed for clearness of illustration. Fig. 2 is a side view, partly in elevation and partly in vertical section, of my ore-crusher with certain parts removed, the removed parts being of ordinary construction and the vertical section being taken on the line 2 2 of Fig. 1.

30 The upper part of my improved ore-crusher, including the shaft, crushing-rolls, and frame, is preferably of the construction shown in the United States patent granted to me April 11, 1899, No. 623,088. In the construction shown 35 in that patent the tread was made solid to pulverize the ore. In my improved ore-crusher the bars forming the tread are placed at a predetermined distance apart, so that when the ore is broken into pieces of the required fineness they will drop between the 40 bars and be collected and taken away for further treatment. The crushing-rolls A break the ore into small pieces, which drop between the bars B of the tread as soon as they reach 45 the desired degree of fineness, which is determined by the distance between the bars of the tread. The bars forming the tread have a slight vibratory movement to prevent the ore from wedging between them and are supported by supports J, which are narrower

than the bar and which rest on suitable supports in the bottom part of the mill. The supports J may be dispensed with by making the bars B stronger than is necessary when used with such supports. I prefer their use, 55 as it enables me to almost completely wear out bars B before it is necessary to replace them. If they are omitted, the bars B must be replaced as soon as they are worn, so that there is danger of their breaking from the 60 weight of the crushing-rolls. These concentric rings rest upon supports J, and each ring is enough larger than the one next to it toward the center to permit the ore when it is crushed to the desired fineness to pass through 65 the spaces left between the rings. As the rolls bear on these rings at four different points at the same time, their weight and movement in different directions, each roll having a sliding motion as well as a rolling 70 one, keep them in place. The sliding motion of the roll causes a slight vibratory motion of the rings as the rolls pass over the different parts of the tread. As the ore drops between the bars it falls upon screen C, which 75 permits the very fine ore to pass through and fall upon deflecting-plate D, from which it slides into trough E, while the coarser particles slide down screen C into trough F.

Attached to the frame which carries the 80 crushing-rolls are two depending arms G, on the lower ends of which are scrapers H to carry the ore collected in troughs E and F to the outlet-spouts I in the bottom of troughs E and F, which carry the ore out of the machine. 85

If it is not desired to separate the crushed ore into two grades, the deflecting-plate D and trough E, one arm, and scraper may be dispensed with, and the screen C may be a 90 deflecting-plate, or the deflecting-plate could run to the center of the mill and connect with a central discharge-spout and both arms, scraper, and troughs dispensed with.

Having described my invention, what I 95 claim is—

An ore-crusher comprising a revolving frame; revolving crushing-rolls mounted in said frame; a tread for said rolls composed of a plurality of concentric rings, having 100

spaces therebetween; supports for said rings; screens below the tread, adapted to deflect the crushed ore into the troughs at the side of and below the tread; arms affixed to the 5 revolving frame, having scrapers on the bottom thereof adapted to work in said troughs.

In witness that I claim the foregoing I have

hereunto subscribed my name, this 11th day of November, 1899, at Los Angeles, California.

CHARLES C. LANE.
